(57) **CLAIM**

The ornamental design for a towel with a tie, as shown and described.

DESCRIPTION

FIG. 1 is a perspective view of a towel with a tie embodying my new design; and,

FIG. 2 is a top plan view thereof; the bottom plan view being a mirror image thereof; the undisclosed side views being flat and having a smooth edge.

1 Claim, 2 Drawing Sheets

FIG. 1

FIG. 2

UNITED STATES PATENT AND TRADEMARK OFFICE
CERTIFICATE OF CORRECTION

PATENT NO. : Des. 603,583 S
APPLICATION NO. : 29/317511
DATED : November 10, 2009
INVENTOR(S) : John Wood

Page 1 of 1

It is certified that error appears in the above-identified patent and that said Letters Patent is hereby corrected as shown below:

On the title page, In Description

Column 2, under Description, "FIG. 2 is a to plan" should be -- FIG. 2 is a top plan --.

Signed and Sealed this

Thirtieth Day of March, 2010

David J. Kappos
Director of the United States Patent and Trademark Office
